UNITED STATES PATENT OFFICE.

DOMINICK A. REAGAN, OF ALTOONA, PENNSYLVANIA.

FIRE-BOX FOR LOCOMOTIVE OR STATIONARY BOILERS.

1,190,952.

Specification of Letters Patent.

Patented July 11, 1916.

Application filed November 11, 1910. Serial No. 591,783.

To all whom it may concern:

Be it known that I, DOMINICK A. REAGAN, a citizen of the United States, residing at Altoona, in the county of Blair and State of Pennsylvania, have invented new and useful Improvements in Fire-Boxes for Locomotive or Stationary Boilers, of which the following is a specification.

This invention relates to fire-boxes adapted for use with either locomotive or stationary boilers, and its primary object is, to provide a fire-box with novel and effective means for promoting combustion, so that the maximum heat from the fuel may be obtained.

A further object of the invention is to increase the area or fire surface of the fire-box, and thus materially add to its heating capacity.

20 A further object is to employ a supplemental hollow grate which serves as a water circulator; furnishes a more even expansion; increases the water space; assists in preventing the formation of scale in the 25 boiler, and also prevents the tubes from direct contact with cold air.

Other objects of the improvement will be disclosed as the description proceeds.

The construction of the invention will be 30 fully described hereinafter, in connection with the accompanying drawing which forms a part of this specification, and its features of novelty will be set forth in the appended claim.

35 In the drawing—Figure 1 is a central longitudinal vertical section of the fire-box of a locomotive boiler equipped with my improvement, and Fig. 2 is an elevation of the water circulator detached.

40 The reference numeral 1 designates a locomotive fire-box provided with the usual fire door 2, and air inlets 3.

The grate bars 4 are the ordinary grate-bars, and extending upward from the fire-box floor in front of the bars 4 is a forwardly and upwardly inclined water circulator 5 extending to a point slightly above the boiler tube 9. As shown in Fig. 2 this device 5 consists of hollow horizontal bars 6 connected to and communicating with hollow parallel side bars 7, the ends of which are screw-threaded to facilitate the attachment of the device to the boiler both at its upper

and lower ends, in order that a free circulation of water may pass therethrough.

55

The space 8 between the circulator 5 and the adjacent ends of the boiler tubes 9 constitutes a space, and it is provided with a clean out door 10, through which ashes may be removed that gain access to said space.

60

The coal not only rests upon the usual grate bars 4, but piles up against the hollow frame or circulating device 5 which constitutes a forward and upward continuation of the grate 4, and materially increases 65 the fire surface as is obvious from the illustration in Fig. 1.

It will be readily perceived that the primary products of combustion are caused to pass through the highly heated incandescent 70 bed of fuel piled against the upper portion of the water circulator 5, whereby said products are superheated and practically consumed, hence a more perfect combustion takes place, the sparks and coal dust being 75 arrested and consumed in the meshes of the said fuel bed, thereby preventing the throwing out of sparks as well as the accumulation of foreign matter in the boiler tubes, and said bed of fuel also prevents the tubes 80 from direct contact with cold air.

The water circulating device also prevents the exhaust pulling unconsumed particles of fuel into the tubes causing the latter to fill up or clog.

85

The supplemental hollow grate may be of such form and area as to meet the requirements of the boiler in connection with which it is used, and if desired may be made of two or more sections to facilitate manipulation 90 or repairs.

While the improvement might be embodied in a variety of constructions, all accomplishing the purposes aimed at, the form here shown clearly shows the invention but 95 I would have it understood that I reserve the right to make all such variations in details as may fall within the terms and scope of the following claim.

Having thus fully described the invention 100 what I desire to secure by Letters Patent and claim is:—

In a fire-box for boilers, the combination with grate bars in the floor of the fire-box and boiler tubes, of a water circulating device 105 extending through the upper floor of

the bottom portion of the fire-box and inclined upwardly and forwardly terminating through the roof of said fire-box thereby forming an inclined rest for the fuel and 5 increasing the fire surface of the fire-box, said water circulating device comprising a series of hollow-spaced bars disposed horizontally between which and through the in-

candescent bed of fuel the products of combustion are caused to pass to the boiler 10 tubes, and side bars to which the horizontal bars are connected.

DOMINICK A. REAGAN.

In presence of—
ANNIE K. MILLER,
E. M. HANAN.
